(57) **CLAIM**

The ornamental design for an electronic lock input dial, as shown and described.

DESCRIPTION

FIG. 1 is a perspective view of an electronic lock input dial showing my new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a perspective view of a second embodiment of FIG. 1;

FIG. 8 is a top plan view of FIG. 7 thereof; and,

FIG. 9 is a rear elevational view of FIG. 7 thereof.

The right side, left side and front elevational views of the second embodiment are identical to FIGS. 3, 4, and 5 respectively.
